Patented Aug. 3, 1915.

UNITED STATES PATENT OFFICE.

ALEXANDER V. JENSEN, OF DEVILS SLIDE, UTAH.

CEMENT-PACKING MACHINE.

1,148,780.

Specification of Letters Patent. Patented Aug. 3, 1915.

Application filed January 28, 1915. Serial No. 4,826.

To all whom it may concern:

Be it known that I, ALEXANDER V. JENSEN, a citizen of the United States, and a resident of Devils Slide, in the county of 5 Morgan and State of Utah, have invented certain new and useful Improvements in Cement-Packing Machines, of which the following is a specification.

This invention relates to improvements 10 in cement packing machines and the object of the invention is to provide an improved feeding or filling mechanism for such machines which shall insure that the bags into which the cement is being filled receive the 15 full standard weight of cement before being removed from the machine.

Another object of the invention is to construct the improved mechanism in such a manner that it may be easily and quickly attached or built into cement packing 20 machines of standard or well known makes without requiring changes in the machine or the operation thereof.

While my invention is designed to be used 25 in combination with cement packing machines of different design and construction, it being a feature of the invention that it is readily adaptable for different types of machines, I will describe and illustrate the invention with reference to one well known 30 type of machine, it being within the purview of a person skilled in the art to adapt my improvements to other types of packing machines.

35 The packing machine to which this disclosure more particularly refers comprises a hopper or container from which the cement is fed into the cement bag by means of a rotating feed wheel. The bag is provided 40 with a suitable valve in its bottom and the machine is provided with a spout which is inserted in said valve. The cement is discharged by the said feed wheel into said spout and passes into the bag.

45 The cut-off of the feeding mechanism is regulated by the weight of the bag. A standard bag of cement is supposed to contain 95 pounds of cement, and the machine is so arranged that when about 92 pounds of 50 cement has been fed into the bag, the latter begins to move downward within a chair which supports the bag as it is being filled. The downward movement of the chair with

the bag causes the spout or tube to move downward past the feed opening of the hopper referred to, the operation being so timed and the parts so arranged that the remaining 3 pounds of cement is supposed to be fed into the bag during the closing movement of the spout. The moment the bag is full, the 55 operator operates a cut-off slide to prevent cement from the hopper from passing out into the air. Thereafter a part of the chair is operated to dump the filled cement bag on a suitable table or conveyer which conveys 60 the full bags away from the machine. A counterweight is provided to regulate and counterbalance the chair and bag of cement, and by means of which the empty chair is again raised to bring the spout into register 65 with the feed opening. The cut off slide is opened and the filling of the next bag commences.

During the operation, as above described, it occurs frequently that the operator operates the cut off slide and the chair as soon as he sees the latter commence to move downward with the almost filled bag. This happens through carelessness, or because he thinks the bag is completely filled, or because he is busy with other bags—the machine usually being arranged to fill a plurality of bags at one time—or for other reasons, and thus it happens that a large percentage of bags of cement are shipped with 70 out being filled to standard weight, thereby causing complaints and trouble as well as economic loss due to dissatisfied cement buyers, etc.

To avoid this trouble and to prevent the 75 operator from removing a bag before the same is filled with the full weight of cement for which the bag is designed, I provide a locking mechanism for maintaining the bag chair in its upright position and to prevent 80 85 tilting of said chair before the bag is completely filled.

To this end my invention comprises such parts and combinations of same as are hereinafter described and claimed and as illustrated in the accompanying drawing in which—

Figure 1 is a vertical sectional view of a typical cement packing machine embodying my invention. Only so much of the machine itself is shown as is necessary to un-

derstand the invention and details are omitted. This figure illustrates the position of the parts just prior to the commencement of the downward movement of the chair and bag which latter is almost filled. Fig. 2 is a detail fragmentary view showing the parts in position just after the bag is completely filled and immediately prior to the removal of the filled bag. Fig. 3 is a detail view illustrating parts of the locking mechanism returning to normal position.

In Fig. 1 the reference numeral 1 denotes the frame of the machine.

2 is the main or feeder shaft to which power is supplied in any suitable manner, not shown. The feeder shaft revolves within a feed box 12 which is located below and forms a continuation of a hopper 8 into which the cement is fed by any suitable means not shown. The feed shaft carries a feeder 13 comprising a plurality of blades or wings 14. The feeder rotates at a high rate of speed and discharges the cement from the feed box 12 into the tube or spout 15 which obviously constitutes a receiving means for the bag. As stated above the spout is inserted through a valve in the bag 16, which valve is diagrammatically indicated at 17, and it will be clear that the spout receives the cement from the feed box and feeds the cement into the bag.

The bag is supported partly on the spout, but the greater weight of the bag as it is filled is supported in the bag chair 18 which is in the form of a large loop having a bottom 19 and sides 18,—only one of which is seen. The sides 18 merge at the top at 20 in a pivot to which is connected a rod 3 which is pivoted within the hopper 8 in a housing and supports the chair at the top. The sides 18 of the chair form an A frame joined at the top by the pivot 20 and having a bottom 19.

The chair is provided with scale cups 21 on its sides 18, on the outside thereof, one on each side, by means of which the chair rests on corresponding scale points 22 on the scale beam 23—which is forked to enable it to pass on the outside of the chair as will be understood. The scale beam rests on one or more knife edges 24 supported on the frame at 25 and carries the weight 26, which may be adjusted by a screw 5 in threaded engagement with the weight as shown. 6 is an adjustable weight stop.

The sides 18 of the chair form inwardly projecting wings 30, one on each side connected by a bridge 31 to which the spout 15 is suitably secured by a spout support 32.

Secured to the bridge 31 is also a clamp bracket 33 to which is pivoted at 34 a sack clamp 35 adapted to clamp the sack on to the spout as shown.

36 is a latch pivoted in the sack clamp 35 at 37.

All of the aforesaid parts are thus supported on and move vertically with the chair 18.

40 is a discharge lever which is formed as a smaller A frame and which is movable inside the A-frame 18, 20. The discharge lever has two sides 40 (only one is seen) joined by an upper bag support 70 and a bottom piece 9. The discharge lever is pivoted at 10 on and within the chair. 75

60 is an adjustably mounted bag bottom provided with lugs 61 adapted to fit into one of several notches 62 on the discharge lever. The bag bottom is scoop-formed and may be adjusted vertically to suit the size 80 of bag used.

The discharge lever carries a handle 43 at the top and a latch release 42.

44 is a hook pivoted on the discharge lever at 45 and provided with an adjustable 85 stop 65.

66 is a spring which urges the hook 44 upwardly into engagement with a fixed hook 47 secured to the machine. The hooks 44 and 47 constitute a locking means or device 90 for preventing premature discharge of the filled bag of cement as will appear more clearly hereinafter.

It follows from the foregoing description that the chair 18 rests on the scale beam 23 95 and is movable vertically together with the spout 15 and surrounding parts, and that the discharge lever 40 moves vertically with the chair to which it is pivoted at 10 and is also adapted to tilt in a vertical plane on 100 said pivot, and that when the operator grasps the handle 43 he is able to tilt the discharge lever on the chair, the side of the discharge lever moving inside the chair side 18 between the latter and the bracket 33. 105

The operation is as follows: The weight 26 is adjusted to counterbalance the weight of the chair and discharge lever with the parts thereon plus the required weight of cement to be filled in the sack. The scale beam therefore rests on stop 6 maintaining the chair in its upper position as shown in Fig. 1 with the hook 44 in engagement with the hook 47, and the spout 15 in register with the discharge opening 51 of the feed box 12. A sack is pushed in over the spout 15 and held against accidental removal by the clamp 35 as is obvious. The operator next operates a cut off slide 52, see Fig. 2, and cement is discharged by the feeder 13, 110 through opening or outlet 51, through the receiving spout 15 and bag valve 17 into the bag. As the bag fills it settles within the discharge lever 40 resting against the upper bag support 70 and also in the bottom support or scoop 60. When the bag is nearly full, its weight causes a downward movement of the chair against the weight 26. When the full quantity of cement has entered the bag, the weight thereof causes the 115

chair to move down to its lowermost position and the rear end of the scale beam moves up until stopped by the adjustable stop 75. The lowermost position of the parts are shown in Fig. 2 where it will be observed that the spout 15 is out of register with the outlet 51 and also that the hook 44 has cleared the hook 47. The operator now takes hold of handle 43 and tilts the discharge lever 40 outwardly. During the first part of this movement the release 42 strikes latch 36 to release the bag, after which the bag is discharged as explained above. As soon as the bag falls out of the chair, the weight 26 causes the latter to rise. The operator thereupon moves the discharge lever back into the chair and the bevel faces 76 on the hooks slide against each other permitting hook 44 to pass under and behind the hook 47 as is clear from Fig. 3 after which the operation may be repeated.

The feature to be particularly observed is, that during the downward movement of the chair, the discharge lever is locked against movement relative to the chair because of the hooks 44 and 47, and only when hook 44 is clear of hook 47 can the bag be discharged.

Without the hooks 44 and 47 the operator could discharge the bag as soon as the chair began to move down and before the bag was filled, it being also understood that the adjustment of the weight 26 is so regulated that only when the chair has completely moved down does the bag contain the required amount of cement.

It will be seen that this invention provides a cheap and easily attached locking device for preventing premature discharge of the full bag. Also, that the length of the engaging portion of the hook 44 may be quickly adjusted by the stop 65 on said hook.

The invention is not limited to the particular type of machine illustrated, and I claim its use on other packing machines and also claim such changes of parts and in the arrangement thereof as well as other modifications within the scope of the claims.

50 I claim:—

1. The combination of a feeding means having an outlet, means for supporting a bag to be filled with the receiving opening of the bag in register with said outlet, mechanism for removing the filled bag from said feeding means and means preventing premature operation of said mechanism.

2. The combination of a feeding means having an outlet, means for supporting a bag to be filled with the receiving opening of the bag in register with said outlet, mechanism for removing the filled bag from said feeding means and means preventing operation of said bag removing mechanism before the said bag has been filled.

3. The combination of feeding means, means for supporting a bag to be filled in a predetermined position with respect to said feeding means, mechanism for removing the filled bag and means preventing the operation of said removing mechanism before the said bag has been filled. 70

4. The combination of feeding means having an outlet, means for supporting a bag to be filled in position to receive material 75 through said outlet, mechanism for removing the filled bag and means preventing the operation of said mechanism while the bag is being filled.

5. The combination of a stationary feeding means having an outlet, means for supporting a bag with its receiving opening in register with said outlet, mechanism for moving said bag receiving opening past said outlet to discontinue the filling of the bag, 80 means for removing the filled bag and locking means for preventing the removal of the bag before it is filled, said locking means comprising a fixed member, a movable member supported on said bag removing means 85 and means for adjusting said movable member.

6. The combination of feeding means having an outlet, means for supporting a bag with its inlet in communication with said 95 outlet, means for moving the bag inlet past said outlet to discontinue the feeding of the bag, mechanism for removing the bag and locking means preventing the removal of the bag while the said outlet and inlet 100 communicate.

7. The combination of feeding means having an outlet, mechanism for supporting a bag in position to be filled from said outlet, means for operating said supporting mechanism to remove the filled bag from the said position to discontinue the filling thereof, bag discharging mechanism and means preventing the operation of said discharging mechanism while the bag is being filled 110 and moved away from the outlet.

8. The combination of a feeding mechanism having an outlet, means for supporting a bag in position to be filled through said outlet, means for operating said supporting means to remove the bag from said outlet when said bag is filled, discharging means and locking means comprising a fixed and a movable member for preventing operation of the said discharging means while 115 the said supporting means are being operated.

9. The combination of a feeding mechanism, means for supporting a bag to be filled therefrom, mechanism for removing 125 said bag from said feeding mechanism after it has been filled, discharging means for discharging the bag from the machine, locking means for preventing premature operation of said discharging means and com- 130

- prising a fixed member, a movable member carried by said discharging means and operatively engaged with said fixed member while the bag is being filled.
- 5 10. The combination of a feeding mechanism, means for supporting a bag to be filled therefrom, means for discharging said bag after it has been filled and locking means for preventing premature operation 10 of said discharging means said locking means comprising a member secured to the said machine, a movable member secured to said discharging means and means for keeping the movable locking member in 15 engagement with the fixed locking member while the bag is being filled.
11. The combination of a feeding mechanism, a bag supporting chair, a discharge lever pivoted on said chair, a fixed locking 20 member, a movable locking member on said discharge lever and adapted to engage said fixed member during the filling of the bag and means for operating said movable locking member.
- 25 12. The combination of a feeding mechanism, means for supporting a bag to be filled from said mechanism, a bag discharging device, a locking mechanism adapted to prevent said device from being operated before a bag is filled and comprising a fixed member, a movable member carried by said discharging device, and in engagement with said fixed member during the filling of the bag, means for automatically disengaging 30 said two locking members when the bag is filled, means for operating said discharging device away from said feeding mechanism to discharge a bag and means on said
- locking members for causing the same to engage automatically when said discharging device is moved back into normal position.
13. In a cement packing machine the combination of means for supporting a bag to be filled with cement, clamping means for said bag, discharging mechanism for discharging the filled bag and means preventing the operation of said discharging means before the bag is filled.
14. In a cement packing machine the combination of means for supporting a bag to be filled with cement, clamping means for said bag, discharging mechanism for discharging the filled bag, means on said discharging mechanism for releasing said clamping means to free the bag and a locking device preventing operation of said means for releasing the bag.
15. In a cement packing machine the combination of mechanism for supporting a bag in position to be filled, a discharge device, means for operating the said supporting mechanism to remove the filled bag, locking means preventing operation of said discharging device before the bag is filled, said locking mechanism being adapted to unlock only when the bag is filled and to automatically re-lock when the said discharging device is brought back into normal position.

Signed at Devils Slide in the county of 70
Morgan and State of Utah this 16th day of
January A. D. 1915.
